UNITED STATES PATENT OFFICE.

JOHN HUMPHRIES, OF KIDDERMINSTER, ENGLAND.

DESIGN FOR CARPET.

Specification forming part of Design No. 6,522, dated March 25, 1873.

To all whom it may concern:

Be it known that I, JOHN HUMPHRIES, of Kidderminster, Worcestershire, in England, have invented a new and original Design for Carpets; and I do hereby declare that the following is a full, clear and exact description thereof, which will enable others skilled in the art to make and use the same, reference being had to the accompanying photographic illustration forming part of the specification.

The nature of my design is fully represented in the accompanying photographic illustration, to which reference is made.

This design consists in a series of ornament-

ed diagonal bars, *a*, on a shaded white ground, and in other ornamented bars, *b*, each inclosing a figure of a square form, one surrounded by a vine, *c*, inclosing a central cross, *d*. The other figure incloses a square figure, *e*, with a dark square, *f*, in the center. The ground outside the bars described represents vines *g*, substantially as set forth.

I claim as my invention—

The design for carpets, as shown.

JOHN HUMPHRIES.
